UNITED STATES PATENT OFFICE.

MAXWELL VIDAYER, OF NEW YORK, N. Y.

MACHINE FOR SEALING AND STAMPING ENVELOPES.

1,421,867.

Specification of Letters Patent.

Patented July 4, 1922.

Application filed June 30, 1917, Serial No. 177,978. Renewed May 25, 1922. Serial No. 563,716.

To all whom it may concern:

Be it known that I, MAXWELL VIDAYER, a citizen of the United States, and a resident of the city of New York, borough of Manhattan, in the county and State of New York, have invented new and useful Improvements in Machines for Sealing and Stamping Envelopes, of which the following is a specification.

10 This invention relates to a machine for sealing envelopes and affixing stamps thereto, and has for its object to improve and simplify the construction of such machines to render the same more certain, efficient 15 and rapid in operation than such machines heretofore constructed.

Among the several improved features of the machine may be mentioned the following: Envelopes may be handled by said 20 machine from a pile in which the envelopes are stacked in a natural way, one upon the other and without any special arrangement or unfolding of the flaps, although, of course, the envelopes are uniformly arranged in the 25 pile. In other words, each envelope of the pile may lie flat, with its flap normally closed upon it but unsealed, and said envelopes will be automatically taken from such a pile, one at a time, and advanced through the machine 30 for the operations of sealing the envelope and affixing a stamp thereto. The machine may, of course, be utilized to either seal the flaps without affixing the stamps, or to affix stamps without sealing the flaps, 35 or to perform both operations as hereinafter described.

A further advantage of the present machine resides in the comparatively slight amount of handling of the envelope required 40 for performing the several operations above mentioned, which conduces to the expeditious operation thereof. In the preferred construction shown, the envelope is advanced through the machine by engagement 45 with successive sets of rolls so located that each set in advance will engage the envelope before it leaves a preceding set, whereby a continuous travel of the envelope through the machine may be effected. It will be 50 noted in the present arrangement that the several operations of receiving an envelope, moistening its flap, sealing said flap and affixing a stamp to said envelope are all performed within the narrow compass of 55 these three sets of said continuously-acting

forwarding rolls. As an accompaniment to this feature, the construction of the machine is otherwise simplified, in consequence of which a far speedier operation of the machine may be attained than with other machines of this character. 60

An example of one of the simplified features of the machine will be found in the means for moistening and sealing the flap. As will be hereinafter more particularly described, each envelope is taken from the supply with its flap folded down upon it and the flap is moistened without unfolding it from this normally closed position upon the envelope. An arrangement is provided for 70 inserting a moistening device beneath the closed down flap and between said flap and envelope, so as to supply moisture to the gummed portion of the flap, after which moistening operation the envelope in its continued travel is engaged by a set of rolls for sealing the flap. 75

A further advantage of the present improvement consists in the stamp affixing mechanism. In affixing the stamp to the 80 envelope, the stamp is preferably moistened, but only upon a portion of its gummed surface, and the means for conveying said stamp from the moistening devices to the envelope are arranged to engage the same 85 only upon its unmoistened portion, whereby the moistened portion of the stamp is carried free from contact with any portion of the machine, except, of course, the moistening devices. This method of handling the stamp 90 prevents the parts of the machine from becoming gummed up from continued contact with the moistened and gummed surface of the stamp. 95

The means for feeding an envelope to the 100 machine are arranged to feed one envelope at a time, and as soon as one envelope is fed into the machine, the feeding means ceases operation until said envelope is forwarded far enough for the machine to receive a new envelope. The devices for thus 105 operating the feeding means are controlled automatically by the advancing envelope, preferably by the engagement of the envelope with the initial forwarding rolls. The advancing envelope, in thus controlling the operation of the feeding means, meets with no resistance in its travel nor is it subjected to any outside feeding pressure other than the natural grip of the forwarding 110

rolls as it passes therebetween. In the preferred construction, the act of each envelope moving into the bite of the forwarding rolls serves to stop the feeding means for any 5 further envelopes, and the departure of each envelope from the forwarding rolls serves to start the feeding means for another envelope.

The operation of the stamp-affixing mechanism is likewise controlled by an advancing envelope entering the bite of a set of forwarding rolls. The stamp-affixing mechanism, when automatically set into operation by an advancing envelope, acts to sever and 10 apply a single stamp to the envelope, advancing to receive it. After applying one stamp, the stamp-affixing mechanism automatically stops, irrespective of what becomes of the envelope which originally set it into motion. 15 Before a new stamp will be fed forward and applied by said affixing mechanism, the previous envelope must first depart from the controlling forwarding rolls, and a new envelope must advance into said controlling 20 forwarding rolls. This action will prevent the machine from continuing to feed and waste stamps, if, for any reason, the controlling mechanism becomes inoperative through the clogging of an envelope therein, 25 or by any other means.

Further advantages and improved features of the machine will become apparent from the following description and the accompanying drawings, which illustrate the 30 preferred embodiment of the invention.

Referring briefly to the drawings:

Figure 1 is a plan view;

Fig. 2 is a side elevation (the machine being at rest);

Fig. 3 is a rear view, partly in section;

Fig. 4 shows the right-hand end of the machine in elevation, with mechanisms in shifted position;

Fig. 5 is a section on line $v-v$ of Fig. 4, 45 illustrating portions of the stamp feed and moistening mechanisms;

Fig. 6 is a detail of the stamp-feed mechanism in shifted position;

Fig. 7 is a plan view, partly in section, of 50 the envelope-flap moistening device and stamp-feed mechanism;

Fig. 8 is a longitudinal section on line 8-8 of Fig. 1, showing the position of the parts after the first envelope has left the pile and has advanced into the first set of forwarding rolls;

Fig. 9 is a similar section, showing the 60 position of the parts when the envelope has advanced into the second set of forwarding rolls;

Figs. 10 and 11 are sectional details more or less diagrammatic of the stamp-affixing mechanism, and showing the position of the parts when the envelope has advanced further along its course through the machine.

Referring more particularly to the drawings, the main frame of the machine is indicated at 1, and the main driving shaft for the moving parts of the machine at 2. This driving shaft may be operated from any suitable source of power or may be rotated as herein shown by a crank handle 3. In the embodiment of the invention as illustrated, an envelope is taken from a pile at E—Figs. 8 and 9—and caused to travel continuously through the machine along a horizontal table 4 by the successive engagement thereof with a series of rolls, so spaced that said envelope is engaged by each set of rolls in advance before it leaves a preceding set. The roll 5 of the first set of forwarding rolls is fixed to said driving shaft 2 and operates, through suitable gears 6 and 7 at one end thereof, its co-acting upper roll 8. Operating shaft 9 for a feeding belt 22 is driven from the main shaft 2 by appropriate gearing, as will be hereinafter described, and lower rolls 10 and 11 of the second and third set of forwarding rolls and ejecting rolls 12, respectively, are mounted in suitable bearings in the main frame and are operated from said driving shaft, as shown in Fig. 1, by means of sprocket chains 13, 14 and 15, which are connected in turn to sprocket wheels fixed to 95 each of said rolls. Roll 10 drives through meshed gears 16 and 17 at one end thereof, its co-acting upper roll 18, and roll 11 similarly drives through meshed gears 18 and 19 its upper co-acting roll 20. Upper roll 21 of the ejecting set of rolls may either be driven positively from its lower roll 12 or preferably by frictional contact therewith, as herein shown. It will be understood that roll 21 is rubber-covered and is mounted in slotted bearings within the main frame, so as to be pressed in frictional contact with said roll 12.

Feeding means.

The envelopes, preparatory to being fed through the machine, are supported upon an endless feeding belt 22 passing around rollers 23 and 9 and over table 26, and having a corrugated upper surface, as shown in Figs. 8 and 9. A spring-pressed arm 24 has a roller 25 for engaging said belt to maintain the same taut. The envelopes indicated at E are stacked above this feeding belt, each envelope lying flat with its individual flap closed down against it, and adjacent to the near side of the machine (see Fig. 7). An adjustable stacking guide 27 may be employed at one side of said belt, and adjacent the forward end of said belt is a fixed but adjustable gate 28, with its lower edge 29 spaced from the upper surface of the belt a sufficient distance to allow but one envelope at a time to pass thereunder. The feeding belt 22 is driven intermittently to 130

feed the envelope successively beneath the gate 28, preferably by the following mechanism:

The roll 8, which is driven continuously from the driving shaft 2, is mounted in slotted bearings within the frame 1 so as to permit a slight vertical movement thereof. One end of said roll shaft 8 has fixed thereto a pinion 30—see Fig. 2—and extends through a bearing in a lever 31, which lever is pivoted at 32 upon the main frame 1. This lever carries pinions 33 and 34, the latter of which is adapted to mesh with pinion 35 upon the feed roll shaft 9. A spring 36, connected to the short end of said lever, normally tends to keep the long end of said lever down, with the roll 8 pressing against roll 5 and gear 34 in mesh with gear 35. While gear 34 meshes with gear 35, the feed belt 22 will be operated to carry the lowermost envelope from the pile E out from beneath said pile, past the gate edge 29 and into the bite of the rollers 5 and 8. As soon as said envelope passes into engagement with said rollers, the upper roll 8 is slightly raised, due to the thickness of the envelope, carrying with it the long arm of lever 31, whereupon gear 34, at the outer end of said arm, is lifted out of mesh with gear 35 of the feed roll shaft 9, thus stopping the operation of said feed belt. When, however, the envelope has passed through the rolls 8 and 5, roll 8 and the long arm of lever 31 drop to again bring gear 34 into mesh with the feed belt drive gear 35, and another envelope is thereupon fed into said rolls 8 and 5. In this manner, the feeding of envelopes from the pile takes place automatically so as to feed but one envelope at a time into the machine.

40 *Flap moistening and sealing mechanism.*

As the envelope, indicated at E', Fig. 8, passes from the initial forwarding rolls 8 and 5, its flap is moistened and as it passes into engagement with the second set of forwarding rolls 18 and 10, its flap is pressed down and sealed thereby. The flap-moistening devices are illustrated more clearly in Figs. 1, 7, 8 and 9, and preferably comprise a thin moistening pad 37 supported from a water tank 38 secured to the main frame 1 of the machine. The pad 37 has a wetted upper surface and extends across the path of the moving envelope slightly above the table 4 (see Fig. 8). It is supplied with moisture from the tank 38 through connection 39 located at one end of said pad. A presser rod 40 is supported from a bracket 42 fixed to the frame 1, in parallel relation to said pad 37, and spaced slightly in advance and above the same, as shown in Fig. 8. Also located in advance of said moistening pad 37 is a deflector blade 41, likewise supported from the bracket 42 fixed to the main frame 1. The deflector blade is spaced slightly above

the table 4 of the machine, to allow an envelope to pass beneath it, and is of suitable contour so as to insert itself beneath the flap of the advancing envelope and raise it slightly and guide it beneath the presser rod 40 and above the moistening pad 37, allowing the body of the envelope to pass beneath said moistening pad 37, as shown in Fig. 7. The presser rod 40 acts to maintain contact of the envelope flap with the moistening pad 37, to insure the moistening thereof. It will be observed that the moistening devices, as thus described, act to moisten the flap without substantially lifting it from the body of the envelope or unfolding it from its normally closed position.

Stamp affixing mechanism.

The envelope E' as it passes into engagement with the rolls 10 and 18, has its flap sealed upon it and also serves to set the stamp-affixing mechanism into operation for affixing a stamp thereto, as will now be described. The stamps are preferably in the form of a strip carried on a let-off reel 42, as indicated in Fig. 2. The stamp strip S is led upwardly over a guide plate 43 into engagement with stamp-feeding rolls 44 and 45, which are intermittently operated, as will be hereinafter described, to feed successive stamps forward into the moistening and applying devices. 46 and 46' indicate the stamp moistening rolls, which are preferably separated to provide a narrow space between them and are mounted in the main frame 100 below the roller 11 for continual rotation with the lower part of their peripheries in a water tank 47. The end of the roll 11, which lies above the moistening rolls 46 and 46', has separated annular portions thereof cut away to provide a narrow edge carrying disk 48 between said cut-away portions. As shown in Fig. 5, the moistening rolls 46, 46' are located opposite the annular cut-away portions of roll 11, and the carrying disk 48 of said roll 11 is located opposite the space between said moistening rolls 46 and 46', whereby, although said roll 11 and said moistening rolls 46 and 46' have a common tangent, they do not come into actual contact with one another.

A narrow endless carrying belt 49 is guided over small pulleys 50, 51 and 52, so as to press against the carrying disk 48 throughout a portion of its periphery in co-acting with the same for conveying a stamp. As shown in Fig. 5, the stamp carrying belt 49 passes through the space between the moistening rolls 46 and 46' and engages only the central portion of the stamp against the disk 48, whereby the marginal portions only of the stamps are carried into contact with the moistening rolls 46, 46'. The stamp is carried around with disk 48 and eventually rolled onto the envelope. 58 and 130

59 are filler rolls located within the annular cut-away portions of roll 11 and carried on pivoted spring-pressed arms 61 and 62, whereby said rolls 58 and 59 are maintained 5 in yielding contact with the upper roll 20 for pressing the moistened part of the stamp upon the envelope as said envelope passes between rolls 11 and 20. The moistening rolls 46 and 46' are positively driven preferably from roll 11, through a train of 10 gears 54, 55, 56 and 57, the last named gear being fixed to said moistening rolls (see Fig. 2). The carrying belt 49 is also positively driven, preferably from end pulley 15 50, the shaft of which at one end has a pinion 60 in mesh with gear 18 of roll shaft 11. The other end belt pulley 52 is preferably mounted in bearings in the rear ends of swinging lever arms 62, 63, said arms 20 being pivoted on a transverse rod 64 of the main frame and connected at their forward ends by a cross member 103 (see Fig. 7). The intermediate belt pulley 51 is mounted in slotted bearings of the main frame (see 25 Fig. 4) and has a spring 65 connected therewith to permit of yielding movement thereof. The belt pulley 52 and belt carried thereby is thus permitted to have a swinging movement toward and away from the 30 stamp-carrying disk 48, so as to facilitate the receiving of and grasping of a stamp as it is fed to said disk and belt by the stamp feeding rolls 44 and 45. The open position of said belt preparatory to receiving a stamp is shown in Fig. 8, and the closed position after seizing said stamp, in Fig. 9. 65 indicates a knife blade for severing a single stamp from its strip as it passes through the rolls 44 and 45, said 35 knife blade being fixed to the upper end of an arm 66 pivoted at 67 upon the main frame, so that said blade 65 may have a swinging movement transversely of said machine (see Fig. 3). The lower end of 40 arm 66 has a pin and slot connection with a swinging lever arm 68 extending fore and aft of the machine, and also pivoted on the rod 64 of the main frame. The means for swinging lever arms 62, 63 and 68 will be 45 later described. Obviously, rollers or other suitable endless means may be substituted for the belt 49.

Control for stamp affixing mechanism.

55 The means for operating and controlling the stamp affixing mechanism will now be described. At one side of the main frame is mounted a rack bar frame, comprising upper and lower horizontal and parallel 60 rack bars 69 and 70 respectively, connected at the ends by vertical struts 71 and 72, which protrude for some distance through the upper bar 69. The rack bar frame is guided for longitudinal movement along the 65 main frame by means of vertical brackets

73 and 74 fixed to said main frame and which are slotted, as shown in Fig. 2, to receive the horizontal members of said rack bar frame. The upper member 69 of said rack bar frame has a loose connection at its 70 ends with the vertical struts 71 and 72, and is yieldingly pressed toward the lower horizontal member 70 by springs 75 and 76 carried on the protruding ends of struts 71 and 72 at each end of said rack bar frame. The lower member 70 of said rack bar frame is also preferably guided at its rear end through rollers 77 and 78.

During the operation of the machine this above-described rack bar frame is given a 80 reciprocating movement in the following manner: Roll 18 is mounted in bearings of the main frame to permit of bodily up and down movement and one end of said roll extends through a bearing within a 85 lever arm 79 pivoted at 80 upon the main frame. The long arm of said lever 80 carries gear 81 and intermediate gear 82, the latter meshing with gear 83 upon said roll shaft 18. The short arm of said lever 79 90 is connected with a spring 84 tending to keep roll 18 down against roll 10. When an envelope as E', Fig. 9, enters the bite between rolls 18 and 10, roll 18 is slightly raised against the force of spring 84, and 95 the long end of arm 79 is likewise lifted to mesh gear 81 with the rack teeth of the upper member 69 of said rack bar frame. Assuming gear 81 is rotating in the direction of arrow, Fig. 4, the rack bar frame 100 will thereupon be moved toward the left, as shown in said figure, until a blank, untoothed portion 85 of said rack bar 69 comes opposite said gear 81. The yielding of upper rack bar 69 permits envelopes of different thicknesses to pass through rolls 18 and 10. When the envelope passes from between the rolls 18 and 10, the roll 18 drops so as to swing gear 81 downwardly and thus cause it to mesh with the teeth of the lower 110 horizontal bar 70 of the rack bar frame, whereupon said rack bar frame will be moved toward the right, until the blanked untoothed portion 86 of said bar comes opposite gear 81 (see Fig. 4). The rack bar 115 will remain in this condition of rest until another envelope enters between the rolls 18 and 10, whereupon this operation will be repeated.

The back and forth movement of said rack bar frame accomplishes the following results. A pin 87, fixed to the lower horizontal member 70 of the rack bar frame on its rearward travel, is adapted to engage a wedge face 88 upon a pawl-carrying arm 89, see Fig. 6. 120 The pawl-carrying arm 89 is pivoted at 90 alongside of a ratchet 91, which ratchet is fixed to the toothed pinion 92, said pinion operating in turn through an intermediate pinion 93, pinion 94 of said lower stamp- 125 130

feeding roll 44; see Figs. 2 and 4. The upper roll 45 is preferably driven by friction from the lower roll, and for this purpose may be rubber covered, as shown. The 5 wedge face 88 upon the pawl-carrier 89 is designed to allow pin 87 to engage the same and swing said pawl-carrier 89 from one side to the other and also to pass away from said wedge-shaped face in either direction. Referring to Fig. 4, a movement of the pin 87 to the right carries the pawl-carrier rearwardly so as to be in readiness for a driving action upon the ratchet 91. A movement of the pin 87 toward the left 10 swings said pawl carrier 89 to actuate said ratchet and through the train of pinions above described, operates roll 44 a sufficient distance to feed one stamp therethrough. Vertically spring-pressed pins 95 and 96 are 15 located at each side of the pawl carrier 89 and are arranged to engage the wedge face 88 thereof when the latter is swung downwardly by the passing of pin 87, so as to raise the same, as shown in dotted lines in Fig. 6, into position for being re-engaged by said pin 87 in its return travel.

Depending from the lower horizontal bar 70 is an L-shaped arm 97 having pins 98 and 99 thereon adapted to alternately come 20 into engagement with an arm 100 fixed to rock shaft 101 mounted in the main frame to swing the same backwards and forward. The short arm 102 also fixed to the rock shaft 101 is adapted to bear against the forward end of the lever 62 (see Fig. 7). The cross piece 103 of said lever arms 62 and 63 carries an adjustable screw stud 104, which is adapted to engage the forward end of the knife-operating lever 68.

25 A spring 105 coiled around said pivot rod 64 normally tends to raise the cross-piece 103, together with the forward end of said knife-operating lever 68, whereby the knife at the rear is normally in raised position and the belt pulley 52 carried in the rear ends of arms 62 and 63 is normally swung away from the stamp-carrying disk 48. The forward movement of the rack bar frame swings the arm 100 down and operates the 30 knife 45 to sever a stamp and swing the belt 49 toward the disk 48 for tightly grasping the stamp, and the rearward movement (to the right looking at Fig. 8) restores the parts to initial position for the next operation.

Operation.

The operation of the machine will be understood from the detailed description here- 35 tofore given, but may be briefly reviewed as follows: An envelope is carried from the bottom of the pile E by the feed belt 22 until its forward edge enters the bite of the rolls 8 and 5. Thereupon roll 8 is lifted 40 to carry gear 34 out of mesh with the feed belt driving gear 35 to stop further feeding of envelopes until the first envelope has passed from beneath said forwarding rolls 8 and 5. As the envelope, indicated at E', Fig. 8, moves over the table 4 between rolls 8 and 5, its flap F is engaged by the deflector 41 and slightly raised so as to pass over moistening pad 37 and under presser rod 40, thus moistening the flap. As the envelope continues to advance and enters 45 the bite of rolls 18 and 10 (see Fig. 9), roll 18 is slightly lifted so as to swing gear 81 (see Fig. 4) upwardly into engagement with the teeth of the upper rack bar 69 (assuming that the rack bar frame is in its rearmost position). The rack bar will thereupon be moved to the left, until it reaches the position shown in Fig. 4, and in this movement the pin 87 on the lower bar 70 will engage the pawl-carrier 89 and, through 50 the train of gearing described, feed a single stamp through the rolls 44 and 45. The pin 99 will at the same time engage arm 100 to depress the lever arms 62 and 63 and also lever arm 68 to operate the severing knife 65 to cut off a stamp. As the stamp is fed through the rolls 44 and 45, pulley 52 and belt 49 hang in the open position (see Fig. 8), so as to readily receive the stamp. Upon the severing of the stamp and the 55 downward movement of arms 62 and 63, the roll 52 and belt 49 are raised against disk 48 so as to firmly seize the stamp at its middle portion and carry the marginal portions into contact with the wetting rollers. The stamp is then carried upwardly to be 60 rolled onto the advancing envelope.

As the stamp is carried by the disk 48 and belt 49 upwardly, it passes between roller 20 and filler rolls 58 and 59 so as to 65 be firmly pressed and sealed against the envelope passing through rolls 11 and 20. Substantially the whole gummed surface of the stamp is pressed against the envelope, while the filler rolls 58 and 59 insure that 70 at least the moistened surface of said stamp is pressed against the envelope. It will be noted that in this operation the moistened portion of the gummed surface of the stamp is carried free from contact with any part 75 of the machine, thus preventing the possibility of the machine becoming gummed up with the accumulated paste. The operating parts are so timed that the engagement of the advancing envelope with the rolls 18 and 20 effects the actuation of the stamp affixing mechanism in time to apply a stamp to said envelope as it passes through the 80 rolls 20 and 11.

As the envelope leaves the rollers 18 and 125 10, the rack bar frame is returned to the right or rear of the machine, ready for the next operation. The envelope in the meanwhile continues on its course through rolls 20 and 11 until it enters between the eject- 130

ing rolls 21 and 12, whereupon it is ejected from the machine with its flap sealed and the stamp firmly affixed thereto.

From the above description it will be observed that my machine is continuous in its operation and comprises a feed device for advancing the envelopes one by one from the pile, forwarding rolls, an envelope flap raiser and flap moistener and stamp affixing mechanism, all arranged in operative alignment, and co-operative to feed envelopes successively from a pile and maintain them in motion longitudinally and without interruption of such motion, progressively moisten and seal the flap, cut off a stamp, moisten a portion only of its gummed surface and affix the stamp to the advancing and continuously-moving envelope, which is automatically ejected from the machine, completely sealed and stamped.

It will be obvious that various changes in specific details and arrangements of parts of the particular embodiment herein disclosed may be made without departing from the spirit and scope of the invention as claimed.

What I claim as new is:

1. In a machine of the class described in combination, means for forwarding an envelope with flap lying against the body of the envelope continuously through said machine, comprising three sets of rolls located in advance of one another so that an envelope is engaged by each set in advance before it leaves a preceding set, and means co-acting with said rolls for moistening and sealing the flap of said envelope and affixing a stamp to said envelope as it passes through said three sets of rolls, said flap being at all times maintained in substantially its original position relative to the body of said envelope.

2. In a machine of the class described in combination, means for forwarding an envelope with flap lying against the body of the envelope continuously in a straight line through said machine, comprising three sets of rolls located in advance of one another so that an envelope is engaged by each set in advance before it leaves a preceding set, and means co-acting with said rolls for moistening and sealing the flap of said envelope and affixing a stamp to said envelope as it passes through said three sets of rolls, said flap being at all times maintained in substantially its original position relative to the body of said envelope.

3. In a machine of the class described in combination, means for forwarding an envelope with flap lying against the body of the envelope continuously through said machine, comprising three sets of rolls located in advance of one another so that an envelope is engaged by each set in advance before it leaves a preceding set, and means

co-acting with said rolls for moistening and sealing the flap of said envelope and affixing a stamp to said envelope as it passes through said three sets of rolls, said flap moistening means acting upon said envelope as it passes between the first and second sets of forwarding rolls, and said flap being at all times maintained in substantially its original position relative to the body of said envelope. 75

4. In a machine of the class described in combination, feeding mechanism for supplying envelopes to said machine, means for forwarding an envelope through said machine comprising several sets of rolls located in advance of one another so that an envelope is engaged by each set in advance before it leaves a preceding set of rolls, said feeding mechanism being automatically controlled by the engagement of an advancing envelope with said first set of rolls, and means co-acting with said several sets of rolls for moistening and sealing the flap of the envelope and affixing a stamp to said envelope as it passes through said rolls. 80 85 90

5. In a machine of the class described in combination, means for forwarding an envelope with flap lying against the body of the envelope through said machine, comprising three sets of rolls located in advance of one another so that an envelope is engaged by each set in advance before it leaves a preceding set, and means co-acting with said first and second set of rolls for moistening and sealing the flap of said envelope while said flap is maintained in substantially its original position relative to the body of said envelope, and stamp affixing mechanism co-acting with the third set of rolls for applying a stamp to said envelope. 95 100 105

6. In a machine of the class described in combination, means for forwarding an envelope through said machine comprising three sets of rolls located in advance of one another so that an envelope is engaged by each set in advance before it leaves a preceding set, and means co-acting with said first and second set of rolls for moistening and sealing the flap of said envelope and stamp affixing mechanism co-acting with the third set of rolls for applying a stamp to said envelope and means operated by the engagement of said second set of rolls with an advancing envelope for controlling the operation of said stamp affixing mechanism. 110 115 120

7. In a machine of the class described in combination, forwarding rolls for an envelope with flap lying against the body of the envelope, flap sealing rolls located for engaging said advancing envelope before it leaves said forwarding rolls, a device located between said forwarding rolls and said flap sealing rolls for applying moisture to said flap while said flap is retained in substantially its original position relative to the 125 130

body of the envelope, and stamp applying rolls located for engaging said envelope before it leaves said flap sealing rolls.

8. In a machine of the class described in combination, forwarding rolls for an envelope with flap lying against the body of the envelope, flap sealing rolls located for engaging said advancing envelope before it leaves said forwarding rolls, a device located between said forwarding rolls and said flap sealing rolls for applying moisture to said flap while said flap is maintained in substantially its original position relative to the body of the envelope, stamp applying rolls located for engaging said envelope before it leaves said flap sealing rolls, and ejecting rolls located for engaging said envelope before it leaves said stamp applying rolls.

9. In a machine of the class described in combination, forwarding rolls for an envelope, flap sealing rolls located for engaging said advancing envelope before it leaves said forwarding rolls, a moisture applying device for said flap sealing operation located between said forwarding rolls and said flap sealing rolls, stamp affixing mechanism comprising stamp applying rolls located for engaging said envelope before it leaves said flap sealing rolls, and means operated by the engagement of the envelope with said flap sealing rolls for controlling said stamp affixing mechanism.

10. In an envelope sealing and stamp affixing machine in combination, a flap moistening surface, a stamp moistening surface, means for advancing an envelope continuously through said machine and affixing a stamp thereto arranged to maintain the moistened part of said flap free from contact with any part of said machine except said flap moistening surface, and to maintain the moistened part of said stamp free from contact with any portion of said machine except said stamp moistening surface.

11. Stamp affixing mechanism comprising a moistening member with a wetted surface for contacting with a marginal portion of the gummed surface of said stamp, and a stamp carrying wheel with a co-acting belt for engaging a central portion of said stamp and carrying the marginal portion of said stamp into contact with said wetted surface and means for affixing the stamp to an advancing envelope.

12. In a machine of the class described, in combination, stamp affixing mechanism, a

pair of positively operated rolls for advancing an envelope to said stamp affixing mechanism, rolls for feeding a stamp to said stamp affixing mechanism, and means operated by the engagement of said first-named rolls with an envelope for effecting the operation of said stamp feeding rolls.

13. In a machine of the class described, in combination, stamp affixing mechanism comprising continuously operating rolls for applying said stamp to an envelope, rolls for advancing an envelope to said stamp affixing mechanism, intermittently operated rolls for feeding a stamp to said stamp affixing mechanism, and means operated by the engagement of said first-named rolls with an envelope for effecting the operation of said stamp feeding rolls.

14. In a machine of the class described in combination, stamp affixing mechanism, forwarding rolls for an envelope, rolls for engaging the envelope before it leaves the forwarding rolls and advancing it to said stamp affixing mechanism, intermittently operated rolls for feeding a stamp to said stamp affixing mechanism, and means operated by the engagement of said second named rolls with an envelope for imparting a limited movement to said stamp feeding rolls to feed a stamp, said means being operable by the disengagement of said second named rolls with said envelope to prepare said stamp feeding rolls for their next feeding operation.

15. In a machine of the class described in combination, opposed rolls for engaging an envelope between them to advance the same, one of said rolls being bodily movable toward and away from the other roll in engaging said envelope, a mechanism for operating upon the envelope and a gear connection controlled by the bodily movement of said roll for actuating said mechanism.

16. In a machine of the class described in combination, opposed rolls for engaging an envelope between them to advance the same, one of said rolls mounted for bodily movement toward and away from said other roll in engaging said envelope and having a movable arm connected therewith, a mechanism for operating upon the envelope and an intermeshing gear carried on said arm for actuating said mechanism and adapted to be moved in and out of operable connection by the movement of said roll and arm.

MAXWELL VIDAVER.
